US00D837790S

(12) **United States Design Patent** (10) **Patent No.:** **US D837,790 S**
Wu (45) **Date of Patent:** **** Jan. 8, 2019**

(54) **MOBILE STORAGE DEVICE**

(71) Applicant: **Transcend Information, Inc.**, Taipei (TW)

(72) Inventor: **Shih-Ting Wu**, Taipei (TW)

(73) Assignee: **Transcend Information, Inc.**, Taipei (TW)

(**) Term: **15 Years**

(21) Appl. No.: **29/573,249**

(22) Filed: **Aug. 3, 2016**

(51) LOC (11) Cl. **14-02**

(52) U.S. Cl.

USPC **D14/435**
